UNITED STATES PATENT OFFICE.

GIULIO GANDOLFO, OF SAMPIERDARENA, ITALY.

ELECTRIC WELDING-MACHINE.

1,306,959.

Specification of Letters Patent. Patented June 17, 1919.

Application filed February 28, 1918. Serial No. 219,653.

To all whom it may concern:

Be it known that I, GIULIO GANDOLFO, a subject of the King of Italy, and residing at 17 Corso dei Colli, Sampierdarena, Province 5 of Genoa, Italy, have invented certain new and useful Improvements in Electric Welding-Machines, of which the following is a specification.

My invention relates to improvements in 10 electric welding machines.

An important object of the invention is to provide a machine of the above mentioned character, the work holding elements or jaws of which are readily removable or interchangeable, the machine being reliable in 15 operation, and convenient to manipulate.

Other objects and advantages of the invention will be apparent during the course of the following description.

20 In the accompanying drawings forming a part of this specification and in which like numerals are employed to designate like parts throughout the same,

Figure 1 is a side elevation of a machine 25 embodying my invention,

Fig. 2 is an end elevation of the same, and,

Fig. 3 is a partly diagrammatic view showing the circuits included in the apparatus.

30 In the drawings, wherein for the purpose of illustration is shown a preferred embodiment of my invention the numeral 5 designates a transformer, embodying a primary coil 6 and a secondary coil 7. As clearly 35 shown in Fig. 3, the primary coil 6 is suitably connected with a source of current 7, and a resistance 8 is connected between the coil 6 and source of current 7. The resistance may be operated for controlling the 40 current passing to the primary coil, and thereby regulating the degree of heat of the work. The resistance 8 may be of any well known or preferred construction and may be operated by turning a hand wheel 9. The 45 resistance is shown supported within or by a frame 10.

Arranged upon the frame 10 are slides 11, adapted to move transversely thereof. These 50 slides receive their movement by screw threaded engagement with a horizontal rotatable shaft 12, the screw threads of which are oppositely pitched. The shaft 12 is turned by hand wheels 13, as shown. The slides 11 are hollow.

55 Arranged above the hollow slides 11 are hollow heads 14, as shown.

Electrodes 15 and 16 are secured to the slides 11, while electrodes 17 and 18 are secured to the heads 14. Jaws 19 are arranged between the electrodes and are suitably secured thereto. These jaws are removable and interchangeable.

A hollow neck or elbow 20 is connected with each end of the primary coil 7, and conduits 21 are connected therewith. These conduits are preferably formed of flexible stripped copper. One pair of conduits 21 is connected with the electrodes 15 and 17, while the other pair of conduits 21 are connected with the electrodes 16 and 18.

70 The numeral 22 designates the pieces of work to be welded.

A water supply pipe 23 leads into the lower end of each slide 11, to supply cooling water thereto. The water discharges from 75 the slide 11 through a pipe 24, which leads into the corresponding upper head 14. The water discharges from the upper end of this head through a pipe 25.

70 The operation of the apparatus is as follows:

The pieces of work 22 are placed within and held by the jaws 19, with their ends in suitably close relation, as shown in Fig. 3. When the dynamo or source of current 7 is 85 set into action, current is induced in the secondary circuit, as is well known. In this secondary circuit current passes from one end of the secondary coil 5, and through the conduits 21, in parallel. The current 90 then passes through electrodes 15 and 17, jaws 19 thereof, the piece of work 22 held by these jaws, the other piece of work, the other jaws 19, electrodes 16 and 18, conduits 21 connected therewith, and back to the opposite end of the coil 5.

It is to be understood that the form of my invention herewith shown and described is to be taken as a preferred example of the same, and that various changes in the shape, 100 size, and arrangement of parts may be resorted to, without departing from the spirit of my invention or the scope of the subjoined claims.

Having thus described my invention what 105 I claim is:

1. In a machine of the character described, a frame, slides arranged thereon for movement toward and away from each other, electrodes carried by the slides, heads arranged near and above the slides, electrodes carried by the heads, jaws arranged between

the electrodes to receive and hold the work, a transformer having primary and secondary coils, means for electrically connecting one pair of electrodes in parallel with one 5 end of the secondary coil, and means for connecting the other pair of electrodes in parallel with the opposite end of the secondary coil.

2. In a machine of the character described, 10 a frame, hollow slides arranged thereon, means to shift the hollow slides toward and away from each other, hollow heads arranged near and above the hollow slides, electrodes carried by the heads and slides, a 15 transformer having a primary and secondary coil, a hollow member having electrical connection with each end of the secondary

coil, a pair of conduits connected with each hollow member and connected with one pair of electrodes, a pipe connected with one hollow member and with the lower portion of one hollow slide, a second pipe connecting the upper portion of the last named hollow slide and lower portion of the corresponding hollow head, and an outlet pipe connected with the upper portion of the last named hollow head. 20 25

In testimony whereof I have signed my name in the presence of two subscribing witnesses the 29th day of October, 1917.

GIULIO GANDOLFO.
